UNITED STATES PATENT OFFICE.

AUGUST E. MEYER, OF DIXON, ILLINOIS.

CURTAIN-PROTECTING DEVICE.

Application filed August 23, 1922. Serial No. 583,776.

To all whom it may concern:

Be it known that I, AUGUST E. MEYER, a citizen of the United States, residing at Dixon, in the county of Lee and State of Illinois, have invented a new and useful Improvement in Curtain-Protecting Devices, of which the following is a specification.

This invention relates to improvements in curtain protecting devices and more especially to a device adapted to be arranged within a window frame in order to prevent curtains or other window hangings or draperies from blowing or otherwise coming into contact with a window screen. The device also prevents the curtain or other draperies from blowing out through the open window, thus preventing soiling or damaging from rain or other outside influences.

In that form of device embodying the features of my invention, shown in the accompanying drawings, Figure 1 is a view in front elevation, showing my improved curtain protector device in place in a window, and Fig. 2 is a view taken as indicated by the line 2 of Fig. 1.

As shown in the drawings, the device comprises two vertical members 10 adapted to be placed within the window frame under the sash as shown in Fig. 1. The vertical members 10 are joined by adjustable horizontal members 12 and 13.

By means of adjustment of the members 12 and 13, the width of the device can be varied in order to accommodate it to window frames of different widths. This adjustment is procured in the following manner. The member 12 at its end carries two wire loops 14, through which the member 13 extends. The member 13 is provided at its end with a spiral wire spring 17 encircling the member 12. The end of the spring 17 is bent toward the member 12 to form a pin 20 adapted to be inserted in any one of a series of holes 22 formed in the member 12. It will be seen that by removing the pin 20, the members 12 and 13 may be slid on each other to adjust the vertical members 10 to the desired width, and then the pin 20 is inserted in the proper hole 22 to retain the adjustment. The spring 17 furnishes a certain amount of yielding movement between the members 12 and 13, so that after the proper adjustment has been

obtained, the vertical members 10 may be pushed toward each other a short distance against the tension of the spring 17, so that they may be placed in the window frame and then released. When so released, the spring 17 separates them a short distance to force the members 10 into the slides in which the window sash 50 operates. The sash 50 is then lowered until it rests on the upper ends of the members 10.

Each of the members 10 is provided with a series of holes 60, each having a slot adjoining it with the edge of the member 10. A string or suitable cord 80 is then laced through the holes 60 as shown. The members 12 and 13 are also provided on their inner faces with a series of slanting slots 93. In lacing the cord 80 through the device, at the center, it is looped, as indicated by 94, through one of the slots 93 in 75 order to give the cord the right tension. Since there are several slots 93 in the members 12 and 13, as shown, the loop 94 may be pulled up to the desired slot 93 in order to take up any slack in the string 80 which 80 there might be, due to the adjustment of the vertical members 10 toward each other to fit narrower windows.

It will be seen that the cord 80 forms a grating or net, preventing any window curtain or other window hanging or drapery from blowing out of the window and coming in contact with the wire screen, or from damage by the elements.

While I have shown and described certain embodiment of my invention, it is to be understood that it is capable of many modifications. Changes, therefore, in the construction and arrangement may be made without departing from the spirit and scope 90 of the invention as disclosed in the appended claims, in which it is my intention to claim all novelty inherent in my invention as broadly as possible in view of the prior art.

What I claim as new and desire to secure by Letters Patent, is:

1. A device of the character described comprising a pair of vertical members, having means for lacing a string thereon to form a grating between said members, and adjusting means joining said members and comprising two horizontally arranged overlapped members, with means for yieldingly holding them in various adjustments and 110

means for taking up the slack in the string caused by the adjustment of the vertical members toward each other.

2. A device of the character described comprising a pair of vertical members, having means for lacing a string thereon to form a grating between said members, and adjusting means joining said members and comprising two horizontally arranged overlapped members, with means for yieldingly holding them in various adjustments and means on said adjusting means for taking up the slack in the string caused by the adjustment of the vertical members toward each other.

3. A device of the character described comprising a pair of vertical members, having means for lacing a string thereon to form a grating between said members, adjusting means joining said members and comprising two horizontally-arranged overlapped members, means for holding the overlapped members in various adjustments, said means comprising a pin mounted on a spring attached to one of the members and adapted to engage in one of a series of

holes in the other member, and means for taking up the slack in the string caused by the adjustment of the vertical members toward each other.

4. A device of the character described comprising a pair of vertical members, having means for lacing a string thereon to form a grating between said members, adjusting means joining said members and comprising two horizontally-arranged overlapped members, means for holding the overlapped members in various adjustments, said means comprising a pin mounted on a spring attached to one of the members and adapted to engage in one of a series of holes in the other member, and means for taking up the slack in the string caused by the adjustment of the vertical members toward each other, said means including a series of slanting slots in one of the horizontal members adapted to engage a loop of the string forming the grating between the vertical members.

Witness my hand and seal this 19th day of August, 1922.

AUGUST E. MEYER. [L. S.]
